United States Patent Office

Des. 193,581
Patented Sept. 11, 1962

193,581

ACCORDION GRILL

Mario Pancotti, 141 Ardsley Road, Scarsdale, N.Y.

Filed Aug. 4, 1961, Ser. No. 66,202

Term of patent 14 years

(Cl. D56—1)

Fig 5

FIG. 1 is a top plan view of an accordion grill showing my new design;

FIG. 2 is a front elevational view;

FIG. 3 is rear elevational view;

FIG. 4 is a side elevational view thereof; and

FIG. 5 is a perspective view thereof on a reduced scale with an accordion being shown in broken lines for illustrative purposes only.

I claim:

The ornamental design for an accordion grill or the like, substantially as shown and described.
